UNITED STATES PATENT OFFICE.

JOSEPH G. SAWICKI, OF ESSEXVILLE, MICHIGAN.

SUBMERGED HEATER FOR TANKS.

Specification of Letters Patent. Patented June 27, 1922.

1,420,759.

Application filed January 26, 1922. Serial No. 531,988.

To all whom it may concern:

Be it known that I, JOSEPH G. SAWICKI, a citizen of the United States, residing at Essexville, in the county of Bay and State of Michigan, have invented certain new and useful Improvements in Submerged Heaters for Tanks, of which the following is a specification.

One of the objects of this invention is to 10 provide a washing machine with an electrical device for heating the wash water.

Another object is the provision of means for enclosing a series of heating elements 15 interiorly of a watertight compartment adapted to be secured to the bottom of a washing machine tank.

A further object is the means provided whereby an electric heating element, adapted to be submerged in water, is constructed in 20 a manner calculated to give a high degree of efficiency and that may be manufactured at low cost.

These and other like objects are attained by the novel construction and arrangement 25 of parts, hereinafter described and shown in the accompanying drawing, forming a material part of this disclosure, and in which:—

Figure 1 is a side elevational view of a 30 washing machine with the side removed to show the position of the heating member.

Figure 2 is a top plan view of the tank and heater with the drum removed.

Figure 3 is an enlarged fragmentary plan 35 view of the heating element, broken away to show the heating units.

Figure 4 is an enlarged partial longitudinal sectional view of the same.

Referring to the drawing in detail, the 40 numeral 6 designates in general the tank of a washing machine having curved bottom 7, concentric with which is rotatably mounted a cylindrical hollow drum 8, perforated and provided with an arcuately curved longitudinal sliding plate 9, giving access to the interior. Means for rotating the drum is shown by the crank handle 10, fixed to a trunnion 11, after passing through the side 45 of the tank 6.

Secured to the inner surface of the curved bottom 7 of the tank, are brackets 13 extending radially inward and supporting a heating element comprising a pair of rectangular members 14 and 15 conformable 50 with and positioned between the drum 8 and the tank bottom 7.

The members 14 and 15 are provided with flanges 16 and 17 extending around the four sides of the elements and a plurality of screws 18 and engaging nuts 18' secure the 60 two elements in water-tight engagement, there being a packing therebetween.

Transverse and longitudinal partitions, respectively 19 and 20, divide the interior into separate compartments adapted to hold 65 the heating coils 21, which may be simple coils of resistance wire or interchangeable resistance units of the replaceable cartridge type.

Insulating bushings 22 are provided 70 through the longitudinal partitions 20, preventing the resistance coils or their terminals from contacting with the metal casing.

Near one of the corners of the casing, is 75 provided a water-tight leading-in bushing 23 clamped through the casing wall by a nut 24, and an opening through the clamp permits the entrance of a suitable electric current carrying cable 25, the conductors 80 of the cable being branched interiorly of the casing, forming lead wires 26 and 27, insulated from the casing by porcelain insulators 28 and 29.

By reference to Figure 3, it will be seen 85 that the lead 27 is disposed along one of the inner sides of the casing and to it is connected one of the terminal ends of each series of resistance coils, and the lead 26 is carried upward and along the opposite side 90 of the casing to be similarly connected to the opposite terminal ends of the coils 21.

The casing members 14 and 15, and the 95 partitions 19 and 20 are preferably made from aluminum castings.

From the foregoing it will be seen that a practical device for the purpose has been disclosed in the preferred form of its embodiment, but changes in the form, construction, proportions and details may be 100 made without conflicting with the scope of the invention as defined by the claims hereto appended.

Having thus described my invention, what I claim as new and desire to secure 105 by Letters Patent, is:—

1. An electric water heater for washing machines comprising a pair of submersible hollow casing members, flanged elements projecting outwardly around said members, 110 said flanges being adapted to fit against each other when said hollow members are

disposed in opposite directions, means for maintaining said flanges in intimate contact, and a packing interposed between said flanges to make a water-tight joint.

5. 2. An electric water heater comprising in combination with a washing machine tank a hollow casing adapted to be separated along its central plane, integral flanges extending outward, means for preventing water from 10 entering therebetween, longitudinal and transverse partitions formed in said casing elements, heating elements consisting of a plurality of resistance units disposed in compartments formed by said partitions, insulating bushings fixed in the longitudinal partition walls, and means for supporting said casing at a spaced distance within the wall of said tank.
- 15 3. An electric water heater for raising the temperature of water contained in the tank of a washing machine, comprising a hollow casing conforming to the contour of the inside bottom of said tank and spaced from the wall thereof, means for connecting said 20 casing to said tank, resistance units forming heating elements contained in said casing and electrically insulated therefrom, means
- 25

for conveying electrical energy to said heating elements, and means for preventing water from entering said casing when submerged.

4. An electric water heater comprising a two part hollow casing, flanged elements extending from said casing, means for holding said casing members tightly together, a 30 plurality of heating elements electrically connected and disposed within said casing, means for insulating said heating elements from the casing compartments formed with the casing and separating said heating elements, means for entering an electric current carrying cable into said casing, said means consisting of a clamp passing through the outer wall of the casing and secured therein by a clamp nut impinging against the casing wall forming a water-tight connection, said cable containing a pair of electrical conductors to one of which are attached one of the terminals from each series of heating elements, while the other conductor is connected to the opposite terminals of the same 40 50 series of heating elements.

In witness whereof I affix my signature.
JOSEPH G. SAWICKI.
